UNITED STATES PATENT OFFICE

ARTHUR T. YATES, OF WEST SENECA, NEW YORK, ASSIGNOR TO BUFFALO FORGE COMPANY, OF BUFFALO, NEW YORK

BENDING ROLL

Application filed November 29, 1930. Serial No. 498,996.

This invention relates to rolls of the type used in connection with bending machines.

The objects of this invention are to provide rolls for bending machines which comprise a number of parts adjustable relatively to each other lengthwise of the axes of the rolls to adapt the rolls for use in connection with work of different cross sectional shapes; also to provide rolls of this kind with means of improved construction for readily adjusting the several parts of the rolls relatively to each other; also to provide a bending machine of this kind in which one of the rolls may be arranged to rotate about its shaft to compensate for variation in the radii of curvature of the inner and outer faces of the work which is being rolled; also to provide rolls of this kind with mechanism of improved construction for adjusting the parts of the rolls relatively to each other; also to improve the construction of rolls of this kind in other respects hereinafter specified.

In the accompanying drawings:

Fig. 1 is a fragmentary elevation of a bending machine provided with rolls embodying this invention;

Fig. 2 is a fragmentary cross sectional view thereof, approximately on line 2—2, Fig. 1, on an enlarged scale, showing the rolls operating on a different piece of work than that shown in Fig. 1;

Fig. 3 is a fragmentary section thereof, on line 3—3, Fig. 1, on a still larger scale;

Fig. 4 is a sectional view thereof similar to Fig. 2, but showing a different adjustment of the parts of the rolls to enable the rolls to be used for bending flat bars flatwise;

Fig. 5 is a similar fragmentary section, showing the rolls adjusted for bending an angle bar with its radial flange extending from the other flange in a direction away from the axis of curvature;

Fig. 6 is a similar fragmentary view, showing the rolls adjusted for rolling an angle bar with its radial flange extending from the other flange in a direction toward the axis of curvature;

Fig. 7 is a fragmentary section thereof, on line 7—7, Fig. 2;

Fig. 8 is a similar section taken on line 8—8, Fig. 4;

Fig. 9 is a section thereof on line 9—9, Fig. 2.

Fig. 1 illustrates this invention as applied to a bending machine, in which the three roll shafts are arranged horizontally, but it will be understood that it is not intended to limit this invention to this type of bending machine, since the rolls embodying this invention are equally applicable to bending machines in which the roll shafts extend in any other direction. In the particular machine illustrated in Fig. 1, A represents the frame of the machine and B, C and D the three bending rolls. The bending machine shown is also provided with the usual guide rolls E for preventing twisting of the work. This particular invention, however, relates only to the construction of the three bending rolls of the machine, and the roll B will herein-after be referred to as the inner roll, since it is nearer to the axis of curvature, about which the work is bent, and the rolls C and D will be referred to as the outer rolls.

The inner roll B is mounted upon a shaft 10 and the two outer rolls are each mounted on a shaft 11. Since the two outer rolls are identical in construction, only one of them will be hereinafter described. The rolls shown are constructed so as to bend flat strips both flatwise and edgewise and to bend angle bars either with a flange extending inwardly toward the center of curvature, or with a flange extending outwardly. It will be understood, however, that it is not intended to limit this invention to rolling the particular shapes shown in the drawings, since obviously the rolls could be used to roll material of other cross sectional shapes without departing from the scope of this invention.

In the particular construction shown, the inner roll includes a substantially cylindrical outer sleeve or part 14, which is located nearest to the outer end of the shaft 10, and an intermediate sleeve part 15 of the same outside diameter as the sleeve 14 and provided on its inner face with an annular recessed portion 16. The roll also includes a ring shaped inner part 17, the outer periphery of

which is preferably of the same diameter as for example, by means of screws or studs 33 (Fig. 1) passing through holes in these plates and engaging threaded holes in the outer roll part. In order to impart lengthwise movement to the outer part of a roll when the stud 31 is turned, a suitable connection is formed between the plate 32 and the stud 31, which connection may, for example, include an integral flange 34 on the stud 31 and a pair of nuts or threaded collars 36 and 37. As shown in the drawings, an integral collar 34 engages the inner face of the connecting member or plate 32 and the nut 36 engages the outer face, the nut 37 acting as a lock nut to hold the nut 36 in the desired position, so as to permit free rotation of the stud 31 relatively to the connecting member 32. To facilitate turning of the stud 31, the end of the stud may be provided with a part 38 which may be engaged by a wrench or other tool for turning the stud. After the desired adjustment of the outer roll part has been effected, the stud can be locked against turning by turning the nut 36 in a direction to clamp the stud to the connecting member or plate 32, and the nut 37 may be used as a lock nut in the usual manner. By means of this construction, it will be obvious that by turning the stud 31 in either direction, the connecting plate or member 32 will be moved toward or from the end of the roll shaft, carrying with it the outer part of the roll, but any other means for adjusting the outer roll part relatively to the shaft and for holding this part in its adjusted position may be provided.

The outer rolls C and D are also each provided with three separate sleeve or ring parts, the outer part 20 being the largest of the three and having on its inner face an undercut annular recess 21 into and out of which an intermediate part or member 22 of the roll 10 may be moved. Each roll further includes an inner part 23 of the same outer diameter as the part 20. Preferably, the roll part 23 has a slight projection 24 near the inner portion thereof which is adapted to enter into a corresponding groove in the roll member 22. In each of the rolls, the inner parts 17 and 23 are not adjustable and are preferably frictionally or otherwise held against movement lengthwise of the roll shafts. The outer 15 and intermediate parts of the rolls are adjustable lengthwise of the roll shafts to adapt the rolls for the various shapes on which they are to operate. The several parts of each bending roll C and D may be held against 20 rotation about their respective roll shafts 11 in any suitable or desired manner, for example, in the case of the outer rolls, by a key 25 fitting in keyways formed in the roll shaft and parts in each outer roll. The parts 14, 15 and 17 of the inner roll may be held 25 against turning relatively to the shaft 10 by means of a key 27 shown in Figs. 4, 5 and 8. An eyebolt 28 may be screwed into the end of this key to facilitate removing of the same, 30 if desired.

The means for adjusting the outer and intermediate parts of the rolls toward and from the inner parts and each other, and for holding the parts in adjusted positions during the use of the machine may be of any suitable or desired construction, the particular adjusting means shown in the drawings being merely an example of one form of such means usable in connection with my invention. Since the adjusting means for all of the three rolls shown is substantially the same, one description applies to all of the three adjusting mechanisms.

The outer parts 14 and 20 of the rolls are 35 preferably adjusted lengthwise of their roll shafts by adjusting means connecting each of these parts with the roll shaft on which it is mounted. In the construction shown for this purpose, the end of each roll shaft is provided with a threaded hole 30 in which a correspondingly threaded stud 31 engages. Upon turning this stud, the lengthwise movement of the stud is imparted to a plate or member 32 which is suitably secured to the outer part of its roll in any suitable manner,

70 which is preferably of the same diameter as for example, by means of screws or studs 33 (Fig. 1) passing through holes in these plates and engaging threaded holes in the outer roll part. In order to impart lengthwise movement to the outer part of a roll when the stud 31 is turned, a suitable connection is formed between the plate 32 and the stud 31, which connection may, for example, include an integral flange 34 on the stud 31 and a pair of nuts or threaded collars 36 and 37. As shown in the drawings, an integral collar 34 engages the inner face of the connecting member or plate 32 and the nut 36 engages the outer face, the nut 37 acting as a lock nut to hold the nut 36 in the desired position, so as to permit free rotation of the stud 31 relatively to the connecting member 32. To facilitate turning of the stud 31, the end of the stud may be provided with a part 38 which may be engaged by a wrench or other tool for turning the stud. After the desired adjustment of the outer roll part has been effected, the stud can be locked against turning by turning the nut 36 in a direction to clamp the stud to the connecting member or plate 32, and the nut 37 may be used as a lock nut in the usual manner. By means of this construction, it will be obvious that by turning the stud 31 in either direction, the connecting plate or member 32 will be moved toward or from the end of the roll shaft, carrying with it the outer part of the roll, but any other means for adjusting the outer roll part relatively to the shaft and for holding this part in its adjusted position may be provided.

90 The intermediate part of each roll, which is the part 15 of the inner roll or the part 22 of an outer roll, may also be adjusted lengthwise of its shaft or of the outermost roll part 95 in any suitable manner. In the construction shown, these adjusting means are mounted on the outermost roll part or on the connecting plate or member 32 secured to the outermost roll part and, therefore, forming a part thereof. For this purpose, a plurality of rods 40 are provided, which extend through holes lengthwise of the outer roll part, the inner ends of the rods being rigidly secured to the intermediate roll parts. In the inner roll three of these rods 40 are provided, and in each of the outer rolls four of these rods are shown. Any desired number, however, may be used in either roll. The outer portions of these rods are threaded, and the threads of the rods 40 engage corresponding internal threads in adjusting sleeves 42 which are journaled to turn in holes or bearings in the connecting plate 32, but are held against movement lengthwise of these holes or bearings. For this purpose, each sleeve 42 has an external thread near the inner end thereof, and has a nut 43 rigidly secured and held against turning on this threaded part, which may for that reason be made tapering, as clearly shown in Fig. 3. The other end of the

sleeve is enlarged, and in the construction shown, is provided with a sprocket wheel 44. Consequently, the sleeves 42 are free to turn in the connecting plates 32, but are held 5 against lengthwise movement therein by the nut 43 and the enlarged end or sprocket wheel 44. It will be obvious that by turning the nuts or adjusting sleeves 42, the intermediate part of the roll will be moved toward or from 10 the adjusting plate through the medium of the rods 40.

The construction described makes it necessary to adjust all of the adjusting sleeves 42 to the same extent, to prevent binding of the 15 intermediate roll part on its shaft, and for this reason, all of the sprocket wheels 44 are connected by means of a sprocket chain 45 so that upon turning one of the adjusting sleeves 42, the same amount of turning motion 20 will be transmitted to each of the other sleeves. This turning may be effected in any suitable manner, and for this purpose, each adjusting nut or sleeve may be provided beyond the sprocket wheel 44 with a head 46 25 which may be engaged by a wrench for turning the same.

By means of the construction described, it will be evident that when the parts are adjusted from the positions shown in Fig. 2 to 30 the positions shown in Fig. 4, it will be necessary first to turn the adjusting sleeves 42 of the outer rolls C and D to draw the intermediate members 22 completely into the recesses 21 of the outer roll part 20. When this 35 has been done, the studs 31 of all three roll shafts may be turned to move the clamping plates 32 toward the ends of the roll shafts until the outer and intermediate parts have been moved into the positions shown in Fig. 4.

4. To make the corresponding change in the inner roll, it is only necessary to turn the stud 31 to move the outer and intermediate roll parts 14 and 15 into close-fitting relation to the roll part 17.

5. When it is desired to move the parts from the positions shown in Fig. 4, into the positions shown in Fig. 5, the studs of the two outer or lower rolls C and D are turned in the opposite direction to move the connecting 50 plates 32 away from the ends of the roll shafts 11. When it is desired to adjust the parts of the inner or upper roll B to the position shown in Fig. 6, the stud 31 is first turned to move the connecting plate 32 away from the end of the roll shaft 10, and the adjusting sleeves 42 are then turned to move the intermediate roll part 15 away from the outer roll part 14.

It will thus be seen that by means of the 60 adjusting means described, any desired adjustment of the intermediate and outer roll parts relatively to the inner roll part may be obtained. Consequently, when the parts are adjusted to the position shown in Fig. 2, a flat bar W may be passed through the rolls to

bend the same edgewise into the desired curvature, the inner edge of the bar entering into a groove or recess formed between the intermediate and inner roll parts 15 and 17 of the inner roll B and the outer edge of the bar W 70 entering between the roll parts 20 and 23 and bearing on the intermediate roll part 22, which in that case is arranged at the base of the slot or groove between the roll parts 20 and 23. When it is desired to bend a substantially flat bar X flatwise, the various parts of the rolls are placed closely together, as shown in Fig. 4, so that the several roll parts cooperate to form rolls with substantially uninterrupted, smooth, cylindrical surfaces. When it is desired to roll an angle bar Y, Fig. 5, with one leg extending radially outwardly from the center of curvature and from the other or cylindrical leg, the parts of the roll B may be left in the position shown 80 in Fig. 4 to form a flat bearing surface for the cylindrical flange of the bar Y, and the parts 20 and 22 of the rolls C and D are moved outwardly to form a space between these parts and the inner roll parts 23 into 85 which the outwardly extending leg of the angle bar may extend during the process of bending.

When the machine is used for bending an angle bar Z with one of its legs extending 90 inwardly toward the radius of curvature from the other leg, the arrangement illustrated in Fig. 6 is employed, in which the parts of the outer rolls C and D are secured closely together, as shown in Fig. 4, and the parts of the inner roll B are so spaced that the two parts 15 and 17 are close together and a gap is formed between the parts 14 and 15 into which the inwardly extending leg of the angle bar may extend. 100

When the rolls are employed for bending a bar in such a manner that there is a considerable difference between the radii of curvature of the inner face of the work engaging the roll B and the outer face of the work 105 engaging the other two rolls, since all of the rolls are positively driven at the same peripheral speed, it will be obvious that a considerable amount of slipping will result. This slipping is very objectionable in that 110 it sets up severe vibrations in the machine. In order to avoid this difficulty, means are provided for having the inner roll B act as an idler roll. For this purpose, in the construction shown, means are provided for readily disconnecting the three parts of the inner roll B from its shaft 10 and in this construction, there is also provided a bearing sleeve 50 between the shaft 10 and the several parts of the inner roll B. This sleeve is split to permit the key 27 to extend through the same and into keyways in the shaft 10 and in the parts of the inner roll B. When it is desired to rotate the inner roll B about its driving shaft, the key 27 may be removed 115 120 125 130

and a half key 51 inserted, as shown in Figs. 1, 2 and 7. This key is arranged in the keyway in the roll shaft 10 and extends into the split part of the bearing sleeve 50 and holds the same against rotation relatively to the shaft 10. The key, however, does not extend into the keyways in the parts of the inner roll B, and consequently, these parts of the roll can turn relatively to the shaft 10. Consequently, referring to Fig. 2, it will be seen that since the radius of curvature of the inner face of the bar W is considerably less than the radius of the outer face of this bar engaging the rolls C and C, the roll B will turn at a slower rate of speed than the other two rolls, so that the parts of the roll B will turn relatively to the bearing sleeve 50. If desired, the half key may also be employed when rolling the flat bar X flatwise, providing the thickness of the bar is great enough to warrant the use of an idle roll. When rolling angles, the bending pressure is exerted only on the flat faces of a leg arranged between the rolls so that the disconnection of the roll B from its driving shaft is not necessary, and also not desirable, since the additional driving force of the inner roll B is necessary to effect the bending of angle bars or similar shapes.

In order to prevent the rotation of the roll about the shaft from turning the stud 31, antifriction fiber washers or similar means 52 and 53 may be employed between the plate 32 and the flange 34 of the stud and the nut 36 respectively. The washers will not interfere with the locking of the stud in fixed position by the use of the lock nuts. Obviously, when the roll B is disconnected from its shaft, the nuts 36 and 37 are backed away from the plate 32 sufficient to permit this plate to turn relatively to the stud 31.

The arrangement of the parts in such a manner that the adjusting means for the intermediate roll part are mounted on the connecting plate 32, forms a connection between the outer and intermediate roll parts, so that the removal of the outer and intermediate roll parts from their shafts can be very readily effected by merely turning the stud 31 to entirely disengage the same from the threaded hole 30, whereupon these roll parts are removed as a unit.

While the invention has been described as applied to rolls for bending flat bars and angle bars, it will be obvious that with slight changes in the shape of the roll parts, the rolls can be adapted for bending work of other shapes.

I claim as my invention:

1. A composite roll for a bending machine, said roll being divided lengthwise of the axis thereof into a plurality of roll parts, at least two of said parts being adjustable lengthwise of the roll relatively to another part and to varying widths, at least one of said roll parts hav-

ing width, at least one of said roll parts having a portion of smaller diameter than the roll diameter and extending into an annular recess of an adjacent roll and movable out of said recess to form a bottom for one of said grooves.

2. A roll for a bending machine, including at least three annular parts mounted on a roll shaft, one of said parts being fixed to said roll shaft and the other parts being adjustable lengthwise of said roll shaft relatively to said fixed part and to each other, said roll parts, when arranged closely together, forming a roll with a single substantially unbroken cylindrical surface.

3. A roll for a bending machine, including at least three annular parts mounted on a roll shaft, one of said parts being fixed to said roll shaft and the other parts being adjustable lengthwise of said roll shaft relatively to said fixed part and to each other, and means forming a connection between said shaft and said adjustable parts for effecting adjustment thereof.

4. A roll for a bending machine, including at least three annular parts mounted on a roll shaft, one of said parts being fixed to said roll shaft and the other parts being adjustable lengthwise of said roll shaft relatively to said fixed part and to each other, and means mounted on said roll shaft and extending beyond the end thereof and connected with said adjustable parts for adjusting the same.

5. A roll for a bending machine, including a plurality of annular parts mounted on a roll shaft, one of said parts being fixed to said roll shaft and the other parts being adjustable lengthwise of said roll shaft relatively to said fixed part and to each other, a member adjustably mounted on the end of said shaft and connected with one of said adjustable roll parts, and means mounted on said member and connected with the other adjustable roll part to effect adjustment thereof relatively to the other parts of said roll.

6. A roll for a bending machine, including a plurality of annular parts arranged successively lengthwise of a roll shaft, some of said roll parts being adjustable lengthwise of the roll shaft to enable the roll parts to be moved together to form a substantially continuous cylindrical surface and to be separated to form annular grooves of varying widths to receive portions of the work which is being bent, at least one of said roll parts having a portion of smaller diameter than the roll diameter to form a bottom for at least one of said grooves.

7. A roll for a bending machine, including a plurality of annular parts arranged successively lengthwise of a roll shaft, an adjustable connection between the outermost of said roll parts and the roll shaft for adjusting said outermost part relatively to the

- other roll parts, and means mounted on said outermost roll part and connected with another roll part for adjusting said other roll part.
5. 8. A roll for a bending machine, including a plurality of annular parts arranged successively lengthwise of a roll shaft, the innermost of said roll parts being mounted in fixed relation to the roll shaft, means connecting the end of the roll shaft and the outermost roll part for adjusting the outermost roll part lengthwise of the shaft, and means movable with said outermost part and connected to an intermediate part for adjusting said intermediate part relatively to said outermost part and said inner part.
10. 9. A roll for a bending machine, including a plurality of annular parts arranged successively lengthwise of a roll shaft, a threaded stud engaging the end of the roll shaft and connected with the outermost of said roll parts for adjusting the same lengthwise of said shaft, and means mounted on said outermost roll part for effecting adjustment of an intermediate roll part.
15. 10. A roll for a bending machine, including a plurality of annular parts arranged successively lengthwise of a roll shaft, a member secured to the outermost of said roll parts and extending crosswise of the end of the shaft, adjusting means connecting the end of the shaft and said member for effecting adjustment of said outermost roll part lengthwise of the shaft, means for adjusting an intermediate roll part lengthwise of said shaft, including rods connected with said intermediate roll part and extending through said outermost roll part, and means located at the outer end of said outermost roll part for effecting adjustment of said intermediate roll part through the medium of said rods.
20. 11. A roll for a bending machine, including a plurality of annular parts arranged successively lengthwise of a roll shaft, means connecting the outermost roll part and said shaft for adjusting said outermost roll part lengthwise of said shaft, rods secured to an intermediate roll part and extending lengthwise through said outermost roll part, means located at the outer end of said outermost roll part for effecting adjustment of said intermediate roll part through said rods, and means connecting said adjusting means to effect a simultaneous adjustment of all of said adjusting means acting on said rods.
25. 12. A roll for a bending machine, including a plurality of annular parts arranged successively lengthwise of a roll shaft, a member secured to the outermost of said roll parts and extending crosswise of the end of the shaft, adjusting means connecting the end of the shaft and said member for effecting adjustment of said outermost roll part lengthwise of the shaft, rods secured to an intermediate roll part and extending crosswise of the end of the shaft, and means connecting said adjusting means to effect a simultaneous adjustment of all of said adjusting means.
30. 13. A bending machine having three rolls, two of which are arranged to bear against the portion of the work of greater radius of curvature and the third of which bears against the portion of the work of lesser radius of curvature, driven shafts on which said rolls are mounted, means for locking said rolls to their shafts to turn therewith, and a bearing bushing arranged between said third roll and its shaft and about which said roll may turn when unlocked from its shaft.
35. 14. A bending machine having three rolls, two of which are arranged to bear against the portion of the work of greater radius of curvature and the third of which bears against the portion of the work of lesser radius of curvature, driven shafts on which said rolls are mounted, keys for securing said rolls to said shafts and fitting into keyways in said shafts and rolls, and a bearing bushing arranged between said third roll and its shaft and slit to permit passage of a key therethrough, said third roll rotating about said bushing when the key connecting the same with its shaft is withdrawn.
40. 15. A bending machine having three rolls, two of which are arranged to bear against the portion of the work of greater radius of curvature and the third of which bears against the portion of the work of lesser radius of curvature, driven shafts on which said rolls are mounted, keys for securing said rolls to said shafts and fitting into keyways in said shafts and rolls, a bearing bushing arranged between said third roll and its shaft and slit to permit passage of a key therethrough, said third roll rotating about said bushing when the key connecting the same with its shaft is withdrawn, and means for securing said bushing against turning about its shaft when said key is withdrawn.
45. 16. A bending machine having three rolls, two of which are arranged to bear against the portion of the work of greater radius of curvature and the third of which bears against the portion of the work of lesser radius of curvature, driven shafts on which said rolls are mounted, keys for securing said rolls to said shafts and fitting into keyways in said shafts and rolls, a bearing bushing arranged between said third roll and its shaft and slit to permit passage of a key therethrough, said third roll rotating about said bushing when the key connecting the same with its shaft is withdrawn.

with its shaft is withdrawn, and a half key, extending only into the keyway of the shaft of said third roll and into said slit in said bushing, to hold said bushing against turning about its shaft while said third roll revolves about said bushing.
